UNITED STATES PATENT OFFICE.

ARTHUR HOWARD LOVEJOY, OF RED BANK, NEW JERSEY.

AIR-HEATER.

No. 873,556.

Specification of Letters Patent.

Patented Dec. 10, 1907.

Application filed February 21, 1907. Serial No. 358,549.

To all whom it may concern:

Be it known that I, ARTHUR HOWARD LOVEJOY, a citizen of the United States, and a resident of Red Bank, in the county of Monmouth and State of New Jersey, have invented a new and Improved Air-Heater, of which the following is a full, clear, and exact description.

The invention relates to heaters for heating buildings and its object is to provide a new and improved air heater made in sections each of which is practically a complete air heater in itself, thus permitting of conveniently setting up any desired number of sections one along side the other, according to the heating capacity required of the heater.

A further object of the invention is to provide a perfect combustion of the fuel and to heat and circulate the air in such a manner that the burning fuel is utilized to the fullest advantage.

The invention consists of novel features and parts and combinations of the same, which will be more fully described hereinafter and then pointed out in the claims.

A practical embodiment of the invention is represented in the accompanying drawings forming a part of this specification, in which similar characters of reference indicate corresponding parts in all the views.

Figure 1 is a cross section of the improvement; Fig. 2 is a longitudinal section of the same; Fig. 3 is a sectional plan view of the same on the line 3—3 of Fig. 2; Fig. 4 is a like view of the same on the line 4—4 of Fig. 2; Fig. 5 is a similar view of the same on the line 5—5 of Fig. 2; Fig. 6 is a perspective view of one of the sections of the heater; Fig. 7 is a diagrammatic view of the smoke circulation, and Fig. 8 is a diagrammatic view of the air circulation.

The air heater in its general construction consists of a front section A, a rear end section B and one or a plurality of intermediate sections C interposed between the sections A and B, as plainly illustrated in the drawings, the several sections A, B and C being fastened together by bolts or other suitable fastening devices, to permit of conveniently increasing or decreasing the number of intermediate sections according to the heating capacity required by the air heater.

The several sections A, B and C form a longitudinally extending fire box or combus-

tion chamber D, a grate E and an ash pit F, that is, each section has a fire box portion D', a grate section E' and an ash pit portion F'. Each grate portion E' is pivoted at its sides, and the several grate sections E' forming the grate E are pivotally connected with a longitudinally extending bar E² passing at its front end to the outside of the front section A, to connect with a hand lever E³ under the control of the operator, for rocking the several grate sections E' in unison whenever it is desired to shake the fuel on the grate E. The front section A is provided with a firing door A', for introducing the fuel into the fire box D, and the said front section A is also provided with an ash pit door A², for removing the ashes from the ash pit F whenever it is desired to do so. The rear section B is provided with an outlet B' for connection with a chimney flue, to conduct the smoke and gases arising from the burning fuel in the fire box D to a chimney or other place of discharge, as hereinafter more fully described.

Each of the sections A, B and C is provided with air heating chambers G, which form the side walls of the fire box D and ash pit F, as plainly shown in Fig. 1, the said air heating chambers being vertically disposed in their lower entrance portions G', which latter are open at the bottom for the entrance of the air from a suitable air duct. The upper portions G² of the air chambers for each section A, B and C are inclined toward each other with the upper ends touching, thus closing the fire box D at the top and making the fire box top peak shape, as shown in Fig. 1. The upper ends of the air-heating chambers G connect with the transversely extending outlets G³, each having a short discharge nipple G⁴ for connection with a flue leading to a room to be heated. Now by the arrangement described the burning fuel in the fire box D heats the air heating chambers G on opposite sides of the fire box, and consequently the air passing through the said air heating chambers in an upward direction, so that the heated air finally passes to the rooms to be heated. It will also be noticed that each section has two distinct air heating chambers located at the sides of the fire box and each connected by a flue with a room to be heated.

Each ash pit section F has a bottom plate F² provided at the under side with transversely extending ribs F³ for raising the bot-

tom of the heater a desired distance above the floor or other support on which the heater is resting.

The upper portions G^2 of the air heating chambers G for the intermediate section C are approximately triangular in shape when viewed in plan, and their inner corners are rounded off, as plainly shown in Fig. 5. The upper portions G^2 of the air heating chambers 5 for the front section A and the rear end section B are irregularly shaped, as indicated in Fig. 4. On the outer sides of the upper portions G^2 of the several sections A , B and C are formed smoke chambers H , H' extending longitudinally one above the other, and of which the upper chambers H are connected by smoke passages or ports H^2 with spaces D^2 formed between adjacent air heating chambers G , as plainly indicated in Fig. 10 5. The front ends of the upper smoke chambers H are connected in the front section A at H^3 with the lower smoke chambers H' , connected at their rear ends with the smoke outlet B' , so that the smoke and gases arising 15 from the burning fuel in the fire box D and passing up into the spaces D^2 pass from the latter through the smoke passages or ports H^2 into the upper smoke chambers H , to travel forward therein and then down at H^3 20 into the lower smoke chambers H' in which the smoke and gases travel rearwardly, to finally pass to the smoke outlet B' . The passage of the smoke and gases above described can be readily traced in the diagrammatic view shown in Fig. 7, in which the 25 arrows indicate the travel of the smoke and gases.

In order to permit convenient cleaning of the smoke chambers H , H' on each side of the 30 heater, the said smoke chambers are provided at each end with entrance chambers H^4 , H^5 , closed at each side of the heater by a suitable door H^6 , which when open permits the insertion of cleaning devices for cleaning 35 the smoke chambers of cinders, soot and the like. Other cleaning doors may be provided at points most advantageous for cleaning the heater.

The space D^3 formed in the rear end section 40 B , between the upper smoke chambers H , is provided in its bottom with an opening D^4 , normally closed by a damper or valve I (see Figs. 2 and 5), and controlled by the operator from the outside by a lever I' connected by a 45 link I^2 with the hinge end of the damper I . Now when the damper I is thrown into an open position, then a portion of the smoke and gases arising in the fire box D can pass through the space D^3 and down the opening 50 D^4 directly into the smoke outlet B' , so as to produce a direct draft in the fire box D whenever it is desired to do so, especially when starting a fresh fire or the like.

On the outer sides of the smoke chambers 55 H , H' are arranged the fresh air chambers J

extending around the heater and separated from each other at the middle of the front section A and the middle of the rear end section B by the use of vertical partitions J' , J^2 (see Fig. 5), and the ends of these fresh air 70 chambers J — J open into the outlet chambers G^3 of the front section A and the rear end section B . The portions of the fresh air chambers J — J formed in the intermediate section C are provided at their bottoms 75 with ports J^3 leading into the air entrance chambers J^4 formed in the intermediate sections C at the outer sides of the lower portions G' of the air heating chambers G (see Figs. 1 and 3). The lower end of each inlet 80 chamber J^4 connects with the air duct, so that fresh air can pass into each individual entrance chamber J^4 , to then pass through the ports J^3 into the fresh air chambers J , from which the air can finally pass to the four 85 outlet chambers G^3 in the front section A and the rear end section B , as above described.

The lower portions G' of the air heating chambers G , in the front section A and the rear end section B are considerably larger 90 than the corresponding portions in the intermediate section C , as plainly indicated in Fig. 3, and the inlet chambers J^4 are omitted in the sections A and B as the front and rear ends of the fresh air chambers J — J open into 95 the air heating chambers G in the said front section A and the rear end section B .

The lower ends of the outer walls of the inlet chambers J^4 are provided with base bars K adapted to rest on the floor or other foundation, the same as the ribs F^3 , it being understood that by the arrangement described the lower ends of the air chambers G and J^4 are free to readily connect with the air duct, for admitting air to both sets of 105 chambers G and J^4 . Now by the arrangement described the smoke chambers H and H' are interposed between the inner air chambers G and the outer air chambers J , and consequently the heat of the smoke and 110 gases passing through the said smoke chambers H and H' is utilized to the fullest advantage, that is, the smoke and gases are caused to travel a long distance before reaching the outlet B' , and during their entire 115 travel in the heater they give off units of heat to the air passing in the adjacent chambers G and J .

In order to prevent dormancy of the air in any one of the air heating chambers G , in 120 case a register in the room is closed, the following device is provided: The inclined top of the outlet chamber G^3 is provided with a damper or valve L having a stem L' extending to the outside, so as to be under the control of the operator for opening and closing the valve L . The latter opens into a longitudinally extending chamber arranged in the top of the heater, as plainly indicated in Figs. 1, 2 and 6, so that when a register is 125 130

closed and a corresponding valve L is opened then air circulates through the corresponding air heating chamber G by passing through the open valve L into the chamber N, thus preventing dormancy in the air chamber G, the register for which has been closed. The air escapes from the chamber N by opening another valve L corresponding to a register that is open.

10 From the foregoing it will be seen that practically each section of the heater contains a portion of the fire box, grate, ash pit, air chambers and smoke chambers, to permit of using more or less intermediate sections C, according to the heating capacity required of the heater. It will also be noticed that by the arrangements described it is not necessary to remove any of the pipes in case new intermediate sections C are to be added 15 or intermediate sections are removed therefrom, that is, the pipe arrangement to the different rooms can be left undisturbed when increasing or reducing the size of the heater. It will further be noticed that in 20 each section, the air to be warmed or heated enters at the bottom and cannot escape at any other point except at the outlet nipples G⁴ at the sides of the heater near the top thereof.

30 By forming the side walls of the fire box D by the air heating chambers G, and by spacing the sides thereof, it is evident that the heat arising from the burning fuel in the fire box D quickly and highly heats the air passing through the said chamber G.

By reference to Figs. 4, 5 and 6, it will be seen that the sides and inner rounded off ends of each heating chamber G are integral and thus present no joints to the heat and smoke 40 of the burning fuel in the fire box; that is, the chambers G project into the fire without one touching the other, and are thus capable of ready expansion and contraction, thereby insuring long life to the heater besides permitting removal of an intermediate section 45 whenever it is desired to do so. It will also be noticed that the air passing through the fresh air chambers J is thoroughly heated before it reaches the corner nipples G⁴ at the 50 front section A and rear end section B, as this additional air has to travel a long distance over the heated outer walls of the smoke chambers H and H'.

Having thus described my invention, I 55 claim as new and desire to secure by Letters Patent:

1. A heater comprising a plurality of sections, each having a fire box, grate and ash pit, air heating chambers on opposite sides of 60 the fire box and ash pit of each section, each air heating chamber being independent and extending from the bottom of the heater and connecting directly with a room to be heated, each section having at each side a smoke 65 chamber located at the outer side of the air

heating chamber, the said heater also having at each side a fresh air chamber at the outer side of the smoke chamber, and an independent air inlet chamber at opposite sides of each section and communicating by ports 70 with the said fresh air chambers.

2. A heater comprising a front section, a rear end section, and a plurality of intermediate sections one alongside the other, the sections forming a longitudinally extending 75 fire box, grate and ash pit, the opposite side walls of the ash pit and fire box of each section being hollow and forming independent air heating chambers each having an inlet at the bottom of the section and a side outlet at 80 the top, the upper portions of the said hollow side walls being inclined toward each other, each section having at each side a smoke chamber, communicating with the fire box, a fresh air chamber on each side of 85 the heater, and an independent fresh air inlet chamber at opposite sides of each section and communicating by ports with the respective fresh air chambers.

3. A heater comprising a front section, a 90 rear section, and intermediate sections between the said front and rear sections, each of said sections forming a portion of the fire box, ash pit, and grate, the hollow side walls of the fire box and ash pit of each section 95 forming air heating chambers extending from the bottom of the section and having an outlet at its upper end for direct connection with a flue leading to a room to be heated, the upper portions of said side walls being inclined toward each other, upper and lower smoke chambers communicating with each other and located at the outer sides of the upper portions of the hollow side walls, the upper portions of adjacent air heating chambers being spaced apart, the spaces between the chambers communicating by smoke passages with the upper smoke chamber. 100

4. A heater comprising a plurality of sections each having a fire box, grate, and ash 110 pit, the side walls of the said fire box and ash pit being hollow forming air heating chambers, the upper portions of the side walls being spaced apart to form smoke passages for the escape of smoke from the fire box, smoke 115 chambers on the outside of the hollow side walls and connected with the said smoke passages, one of the end sections of the heater being provided with a smoke outlet connected with the smoke chambers, the said end 120 section having a space communicating directly with the fire box and provided with a valve controlled opening communicating with said smoke outlet.

5. A heater comprising a plurality of sections one alongside the other and each having a fire box, grate and ash pit, the side walls of the ash pit and fire box being hollow forming air circulating chambers each extending from the bottom of the section and 125 130

connecting directly with a flue leading to a room to be heated, the upper portions of the side walls forming the air circulating chambers being inclined toward each other and 5 spaced apart to form smoke passages for the escape of smoke from the fire box, smoke chambers on the outside of the upper inclined portion of said hollow side walls and located one above the other, the upper 10 smoke chambers being connected with the said smoke passages and with the front ends of said lower smoke chambers, the rear end section of said heater being provided with a smoke outlet connected with the rear ends of 15 the lower smoke chambers, the said end section being formed with a space communicating with the fire box and provided with an opening communicating directly with said smoke outlet, and a manually controlled 20 valve normally closing said opening.

6. A heater comprising a front section, a rear end section, and intermediate sections between the said front and rear end sections, each of the said sections forming a portion of 25 the fire box, ash pit and grate, the hollow side walls of the fire box and ash pit of each section forming an air-heating chamber, the upper portions of the said side walls being inclined towards each other, the said upper portions 30 on each side of the heater being spaced apart to form smoke passages for the escape of the smoke from the fire box, and smoke chambers on the outside of the hollow side walls and one above the other, the upper 35 smoke chamber being connected with the said smoke passages and with the lower smoke chamber.

7. A heater comprising a front section, a rear end section, and intermediate sections 40 between the said front and rear end sections, each of the said sections forming a portion of the fire box, ash pit and grate, the hollow side walls of the fire box and ash pit of each section forming an air-heating chamber, the upper 45 portions of the said side walls being inclined towards each other, the said upper portions on each side of the heater being spaced apart to form smoke passages for the escape of the smoke from the fire box, smoke chambers on 50 the outside of the hollow side walls and one above the other, the upper smoke chamber being connected with the said smoke passages and with the lower smoke chamber, and a smoke outlet for the said lower smoke chamber to conduct the smoke to the chimney flue.

8. A heater comprising a front section, a rear end section, and intermediate sections between the said front and rear end sections, each of the said sections forming a portion of 60 the fire box, ash pit and grate, the hollow side walls of the fire box and ash pit of each section forming an air-heating chamber, the upper portions of the said side walls being inclined towards each other, the said upper 65 portions on each side of the heater being

spaced apart to form smoke passages for the escape of the smoke from the fire box, smoke chambers on the outside of the hollow side walls and one above the other, the upper smoke chamber being connected with the said 70 smoke passages and with the lower smoke chamber, a smoke outlet for the said lower smoke chamber, and means for connecting the said upper smoke chambers directly with the said smoke outlet. 75

9. A heater comprising a front section, a rear end section, and intermediate sections between the said front and rear end sections, each of the said sections forming a portion of the fire box, ash pit and grate, the hollow 80 side walls of the fire box and ash pit of each section forming an air-heating chamber, the upper portions of the said side walls being inclined towards each other, the said upper portions on each side of the heater being spaced 85 apart to form smoke passages for the escape of the smoke from the fire box, and smoke chambers on the outside of the hollow side walls and located one above the other, the upper smoke chamber being connected with the 90 said smoke passages and the front ends of the upper smoke chambers being connected with the front ends of the said lower smoke chambers.

10. A heater comprising a front section, a rear end section, and intermediate sections between the said front and rear end sections, each of the said sections forming a portion of the fire box, ash pit and grate, the hollow side walls of the fire box and ash pit of each 100 section forming an air-heating chamber, the upper portions of the said side walls being inclined towards each other, the said upper portions on each side of the heater being spaced apart to form smoke passages for the escape 105 of the smoke from the fire box, smoke chambers on the outside of the hollow side walls and located one above the other, the upper smoke chambers being connected with the said smoke passages and with the front ends 110 of the said lower smoke chambers, and a smoke outlet at the rear ends of the said lower smoke chambers.

11. A heater comprising a front section, a rear end section, and intermediate sections 115 between the said front and rear end sections, each of the said sections forming a portion of the fire box, ash pit and grate, the hollow side walls of the fire box and ash pit of each section forming an air-heating chamber, the 120 upper portions of the said side walls being inclined towards each other, the said upper portions on each side of the heater being spaced apart to form smoke passages for the escape of the smoke from the fire box, smoke 125 chambers on the outside of the hollow side walls and located one above the other, the upper smoke chamber being connected with the said smoke passages and the front ends of the upper smoke chambers being con- 130

- nected with the front ends of the said lower smoke chambers, a smoke outlet at the rear end of the said lower smoke chambers, and a manually controlled means for connecting the rear ends of the upper smoke chambers with the said smoke outlet.
12. A heater comprising a front section, a rear end section, and intermediate sections between the said front and rear end sections, each of the said sections forming a portion of the fire box, ash pit and grate, the hollow side walls of the fire box and ash pit of each section forming an air-heating chamber, smoke chambers outside the said hollow side walls and located one above the other, the upper smoke chambers being in communication with the lower smoke chambers and with the said fire box, and fresh air-circulating chambers, one on each side of the heater and located outside of the said smoke chambers.
13. A heater comprising a front section, a rear end section, and intermediate sections between the said front and rear end sections, each of said sections forming a portion of the fire box, ash pit and grate, the hollow side walls of the fire box and ash pit of each section forming air heating chambers having air inlets at the bottom and terminating at their upper ends in transversely extending outlets, smoke chambers outside the said hollow side walls and in communication with each other and with the said fire box, and fresh air circulating chambers one on each side of the heater and located outside of the said smoke chambers, the ends of the said fresh air chambers being connected with the outlets of the air heating chambers of said front and rear sections of the heater.
14. A heater comprising a front section, a rear section and intermediate sections between the said front and rear end sections, each of said sections forming a portion of the fire box, ash pit and grate, the hollow side walls of the fire box and ash pit of each section forming air heating chambers, each having an inlet at the bottom of the heater and a transversely extending outlet at its upper end, smoke chambers outside the said hollow side walls and located one above the other, the upper smoke chambers communicating with the fire box and with the lower smoke chambers, and fresh air circulating chambers one on each side of the heater and
- located at the outside of said smoke chambers, the said air circulating chambers being separated from each other at the middle of the front and the rear sections of the heater, the said intermediate sections of the heater each having a separate fresh air inlet chamber connected with the fresh air circulating chambers and located at the outer sides of the lower portions of the air heating chambers, the ends of the fresh air circulating chambers opening into the outlets of the air heating chambers of said front and rear sections of the heater.
15. A heater comprising a front section, a rear end section, and intermediate sections, the said sections forming a longitudinally extending fire box, grate bar, and ash pit, each section having at each side an air-heating chamber, a smoke chamber, and a fresh air chamber, each air heating chamber being independent and located at the side of the fire box and the ash pit.
16. A heater comprising a front section, a rear end section, and intermediate sections between the said front and rear end sections, each of the said sections forming a portion of the fire box, ash pit and grate, the hollow side walls of the fire box and ash pit of each section forming an air-heating chamber having an air inlet at the bottom and an air outlet at the side of the upper portion adapted to connect directly with the flue leading to a room to be heated, a longitudinally extending channel between the said air outlets on both sides of the heater the walls of the said channel being made in sections corresponding with the sections of the heater, manually controlled valves for connecting each outlet with the said channel, smoke chambers at the outer sides of the air heating chambers, and communicating with the fire box, and fresh air circulating chambers on each side of the heater, and connected with the outlets of the air heating chambers in the front and rear sections of the heater.
- In testimony whereof I have signed my name to this specification in the presence of two subscribing witnesses.
